UNITED STATES PATENT OFFICE.

LAWRENCE M. PERSONS, OF QUINCY, ILLINOIS, ASSIGNOR TO COOK ELECTRIC COMPANY, OF CHICAGO, ILLINOIS, A CORPORATION OF ILLINOIS.

STARTING SWITCH.

Application filed October 20, 1920. Serial No. 418,305.

To all whom it may concern:

Be it known that I, LAWRENCE M. PERSONS, a citizen of the United States, residing at Quincy, in the county of Adams and State of Illinois, have invented certain new and useful Improvements in Starting Switches, of which the following is a specification.

My invention relates to starting switches particularly adaptable for use in alternating current motors, and has for one of its objects the provision of a simple and efficient switch for cutting in and out an auxiliary winding used in connection with starting an alternating current motor.

Another object is the provision of a simple and efficient starting switch of the character mentioned which can be easily put together and taken apart.

A further object is the provision of a starting switch of the character mentioned having no screws, bolts, or the like, used therein.

A still further object is the provision of a switch of the character mentioned of simple construction as hereinafter described and more fully set forth in the appended claims.

An embodiment of my invention is shown in the accompanying drawings, forming a part of this specification, and in which—

Fig. 1 is a fragmental section showing a portion of an electric motor equipped with a switch embodying my invention;

Figs. 2 and 3 are similar views taken as from line 2—2 in Fig. 1 with the switch mechanism in Fig. 2 in different positions than in Fig. 3;

Fig. 4 is a fragmental transverse section showing my switch device partially assembled; and

Fig. 5 is a longitudinal section showing parts of my switch and fragments of an electric motor disassembled.

Referring more particularly to the drawings, I have indicated a fragment of an electric motor having a field core 6 having two sets of windings thereon, the terminals 7 and 8 of one of the windings being brought out and secured to an insulating block 9 on the motor cap 10. One terminal 11 of the other winding on the field core 6 is connected with the terminal 7 under a screw 12 in block 9 where it is adapted to be connected with the feed circuit, not shown.

The other terminal 13 of the second-mentioned winding on the core 6 is secured to a contact member 14 on the cap 10 and insulated from the latter by insulation 16. Also, on the cap 10 is a contact 17 secured thereto and insulated therefrom by an insulation 16. From the contact 17 a wire 18 connects with the terminal 8 of the first-mentioned winding on core 6 and is connected to the insulating block 9 by a screw 19. The screw 19 is adapted to be connected with the other wire of the supply circuit, not shown.

A bearing 20 is provided in the cap 10 and in said bearing is journaled a motor shaft 21 which carries an armature 22. The field core and its windings and the armature may be of any conventional or preferred construction used in alternating current motors.

My improved switch and its operating mechanism comprises two weights 23, which in the present instance are indicated as semi-cylindrical members of sheet material each pivoted on an axis at one side of the axis 80 of the shaft 21. The weights 23 may be pivoted in any desirable manner, but to make them easily assembled and disassembled I prefer to provide openings 24 in suitable portions of the adjacent end of 85 armature 22 with substantially semi-circular ears 25 on the weights disposed in said openings 24. When the weights 23 are in their positions shown in Figs. 2 and 3, the ears 25 will be securely locked in the openings 24, but when some of the parts are removed from the switch and the weights are in their positions shown in Fig. 5, they may be slid longitudinally of the shaft to remove the ears 25 out of openings 24.

Around the shaft I provide a ring 26 which has two arms 27 thereon. The arms 27 have their outer ends disposed in openings 28 in the weights 23. The arms are preferably of such lengths that when the ring 26 is substantially concentric with shaft 21 the arms will be in openings 28 even when the weights 23 are in their outmost swinging positions, such as indicated in Fig. 3. By moving the ring 26 first toward one side 100 of the shaft and then the other the arms 27 may be removed from the openings 28. In use I provide a tube 29 between shaft 21 and ring 26 to hold the latter concentric with said shaft. The member 29 also serves as a 110

spacing means between the cap 10 and armature 22. I have indicated a fiber or other friction-alleviating washer 30 between the end of sleeve 29 and cap 10 which is usually provided in motors of this kind.

5 The weights 23 are provided with a spring 31 or other resilient means which tends to swing them toward shaft 21. The ring 26 is provided with a restricted portion 32 on 10 which is rotatably mounted a fiber or other insulating washer 33. The washer may be held from moving off the end of ring 26 in any desirable manner, such as by a spring wire 34 disposed in a groove around the 15 end of said ring 26, as clearly indicated in Fig. 3. On the outer edge of the washer 33 is an electrical conductor ring 35 adapted to engage contacts 14 and 17 to complete the circuit through terminals 13 and 11 of one 20 of the coils on core 6. I preferably mount the washer 33 and its ring 35 in such a manner that it is free to rotate on ring 26 and also provide it with limited longitudinal movement with relation to said ring.

25 It will be noted that with this construction by removing screws 36 which hold the cap 10 in place, this cap being a part of the motor casing, my improved switch can be taken apart and put together without removing any other screws or bolts. In assembling the device in the first place, the ears 25 are hooked into the openings 24 when the weights 23 are in their positions indicated in Fig. 5, then the ring 26 with its arms 27 30 are placed between the weights and the arms inserted in openings 28, as indicated in Fig. 4. The tube 29 is then placed between ring 26 and shaft 21. When the washer 33 has been taken off the ring 26, wire 34 can be 35 sprung into its groove after said washer is placed on its restricted portion of ring 26. When the cap 10 is placed in position the switch is ready for use. To disassemble, the reverse order of procedure is had.

40 In use the winding of the field 6 are such that the winding having the terminals 7 and 8 are the one which operate the motor after it has attained its designated speed. In order to bring the motor up to its designated speed the coil having terminals 11 and 13 are wound on the field in a manner to cause the motor to come up to its designated speed upon current being admitted to screws 12 and 19. When the motor is at rest spring 45 31 pulling on the weights 23 holds the contact member 34 in engagement with contacts 14 and 17 thereby completing the starting circuit of the field 6. Upon current being introduced at points 12 and 19 the armature 50 starts to revolve and the centrifugal force in weights 23 moves the ring 26 longitudinally of tube 29 and draws the contact 35 away from the contacts 14 and 17. The spring 31 has sufficient tension so that the 55 contact 35 will not be disconnected from

contacts 14 and 17 until the motor reaches its designated speed. As soon as the contact 35 is disconnected from contacts 14 and 17 the circuit having terminals 11 and 13 is broke and the motor continues to operate 70 on the field circuit having terminals 7 and 8. I preferably form the ring 26 and tube 29 so that there is slight play between them. Also, the opening in washer 33 is slightly larger than the restricted portion 32 so that 75 the contact member 35 can always engage both of the contacts 14 and 17 easily. By making these parts fit loosely it will be seen that they will shift sufficiently to accommodate always getting good contacts between 80 the member 35 and members 14 and 17.

An important feature of the particular arrangement of the contact-making parts is having the member 33—35 loosely mounted so that when it is moved away or comes into engagement with the contacts 14 and 17 it tends to brighten up the engaging surfaces as it leaves or engages said contacts 14 and 17. When leaving the contacts 14 and 17 as it begins to revolve it rubs on the surface of contacts 14 and 17. When it comes into engagement with said contacts 14 and 17 its inertia causes it to rotate a very short time upon engaging said contacts, thereby 90 keeping the contacting surfaces in good conducting condition.

I claim:—

1. A motor starting switch comprising a motor shaft; a weight pivotally mounted to swing relative to said shaft; a ring around said shaft and slidably longitudinally thereof; an arm on the ring engaging said weight; a spacing tube spacing said ring from said shaft; a fixed contact; and a contact on said ring having limited longitudinal movement with respect to the latter and adapted to be moved by said ring into engagement with said fixed contact. 100

2. A motor starting switch comprising a motor shaft; a weight mounted for swinging toward and away from said shaft; a ring around said shaft and slidably longitudinally thereof; an arm on the ring engaging said weight; a tube spacing the ring from said shaft; a fixed contact; and a contact rotatably mounted on said ring adapted to be moved thereby into engagement with said fixed contact. 110

3. A motor starting switch comprising a motor shaft; two weights pivoted on spaced axes at the sides of the axis of said shaft; resilient means tending to swing said weights toward said shafts; a ring around said shaft and slidably longitudinally thereof; arms on the ring engaging said weights; a tube between said ring and shaft; a fixed contact; and a contact rotatably mounted with respect to the shaft adapted to engage said fixed contact. 120

4. A motor starting switch comprising a 130

- motor shaft; pivotally mounted weights each having an opening therein; a ring around said shaft and slidably longitudinally thereof; arms on the ring engaging said openings; 5 a tube spacing the ring substantially concentrically around the shaft and holding said arms in said openings; a fixed contact; and a contact carried by said ring adapted to engage the fixed contact.
- 10 5. A motor starting switch comprising a motor shaft; pivotally mounted weights on opposite sides of said shaft with each weight having an opening therein; a ring around said shaft; arms on said ring engaging said 15 opening; a tube spacing the ring substantially concentrically around the shaft; a fixed contact; a contact rotatably mounted on said ring and having limited longitudinal movements with respect to the ring; and a 20 spring tending to pull said weights toward each other.
6. A motor starting switch comprising a shaft; an armature on the shaft; a motor cap having a bearing therein in which an end of the shaft is journaled; weights pivoted on 25 the armature; a ring around the shaft; arms on the ring engaging the weights; a spring attached to the weights; and a tube spacing the ring from the shaft and the cap from the armature. 30
7. A motor starting switch comprising a shaft; an armature on the shaft; two weights pivoted to the armature at opposite sides of the shaft and having openings therein; a spring between the weights tending to swing the latter toward said shaft; a ring around the shaft; arms on the ring extending in said openings; and a tube between the ring and shaft holding the spring in said openings, 35 the ring, arms and tube being arranged to permit removal of the arms from said openings when the tube is removed from between said shaft and ring.

In testimony whereof I have signed my name to this specification on this 28th day 40 of September, A. D. 1920. 45

LAWRENCE M. PERSONS.
